UNITED STATES PATENT OFFICE

2,346,813

BELLOWS OPERATED ANTIFLOODING DEVICE FOR LIQUID FUEL BURNERS

James L. Breese, Santa Fe, N. Mex., assignor to
Oil Devices, Santa Fe, N. Mex., a limited partnership of Illinois

Application July 11, 1941, Serial No. 401,918

2 Claims. (Cl. 158—42.4)

My invention relates to an improvement in controls for oil burners and is particularly applicable to pot type burners.

It has for one purpose the provision of means for completely cutting off the supply of oil in the event that the fire goes out.

Another purpose is the provision of improved thermally operative control means for valves of a fuel supply control means particularly adapted for use with a burner in which a pilot flame is localized at one point in the burner.

Other purposes will appear from time to time in the course of the specification and claims.

I illustrate my invention more or less diagrammatically in the accompanying drawing wherein:

Fig. 1 is a vertical section;

Fig. 2 is a section of the valve structure on an enlarged scale, with the valve illustrated in closed position;

Fig. 3 is a partial plan view of the structure shown in Fig. 2;

Fig. 4 is a section on the line 4—4 of Fig. 2;

Fig. 5 is a similar section with the parts in a different position;

Fig. 6 is a similar section with the parts in a still different position; and

Fig. 7 is a side elevation of a variant form.

Like parts are indicated by like symbols throughout the specification and drawing.

Referring to the drawing, I illustrate a burner pot 1 having a side wall 2, provided with primary air inlets 3 located at various levels. I may employ any suitable means for supplying secondary air. I illustrate a row of secondary air inlets 4 adjacent the top of the pot 1. 5 is any suitable flame ring for the top of the pot, having a central aperture 6.

The pot is supported on a flange or ring 7, extending inwardly from any suitable outer housing or drum 8, the upper portion of which above the pot may provide a combustion chamber. Below the pot the drum 8 has a bottom 9, with an air inlet aperture 10, through which air may be admitted to the space between the pot 1 and the drum 8.

Any suitable supporting means may be employed for the structure, it being understood that the space below the partition 9 is open to the atmosphere or is in communication with some air supply means.

12 is a pilot piece, herein shown as a foraminous structure. 13 generally indicates a liquid fuel inlet nozzle fitting, having a nozzle portion proper 14, and any suitable securing nut 15. In

communication with the fitting 13 is the fuel line 16, extending from a float chamber generally indicated as 17. The float chamber 17 is shown as including a filter chamber 18, with a filter 19 therein. 19a indicates a liquid inlet line from any suitable source of liquid fuel not herein shown.

In communication with the filter chamber is a liquid fuel inlet passage 20, with its valve seat member 21. 22 is a valve stem movable toward and away from the seat 21, mounted for example in the sleeve 23, with the fuel outlets 24, the sleeve in this instance being made unitary with the valve seat. 25 is any suitable float, pivoted on any suitable pin 26 and having a portion 27 at the opposite side of the pivot, engaging a washer or flange 28 on the valve stem, which is normally upwardly urged as by the spring 29.

30 indicates the fuel in the float chamber, and it will be understood that the level in the float chamber is governed by the float 25, which as it is raised by the fuel 30 tends to close the valve stem 22 and reduce or cut off the flow of fuel through the passage 20. Within the float chamber is an intermediate partition 35, which divides the interior of the float chamber into two compartments. In one compartment is located the above described float 25, and in the other a supplemental float 36, secured as at 37 to a lever 38, pivoted as at 39, and having an end portion 40 extending outwardly through a slot 41 in the side of the float chamber structure. It also has an abutment portion 42 adapted to be opposed to the top of the stem 43 of the valve stem 22.

35 In the event that the float 25 or the valve 22 become stuck, or if for any reason the float structure does not function, fuel may overflow the partition 35 and raise the float 36, thus depressing the portion 42 and closing the valve.

40 However, in my invention I employ a lever 38, or its equivalent, to permanently cut off the liquid fuel in the event that the burner goes out. For this purpose I provide any suitable temperature responsive member, which is located adjacent the pilot piece 12. I illustrate, for example, a thermo-bulb 45 connected by a hollow tube 46 to a bellows 47, mounted on the top of the float chamber 17. Normally, when the burner is on and the pilot flame is burning, the bellows 47 is in the expanded position in which it is shown in Figs. 1 and 6. Mounted on the top of the bellows structure is a support 48, to which is loosely pivoted an arm 49, which tends by gravity to take a vertical position and which is aligned with the outwardly extending end of the lever 40.

Assume that the burner is on and a supply of fuel is flowing. The arm 49 is out of contact with the lever 40 and performs no function. If, however, the pilot flame goes out and the pot becomes entirely cold, then the bellows 47 collapses to the position in which it is shown in Figs. 2 and 4, and the arm 49 engages the end of the lever 40 and thrusts it down into the valve closing position in which it is shown in Fig. 2, thus closing the valve 22 and preventing any further supply of fuel to the float chamber along the passage 19a, entirely independent of the operation of the floats 25 or 36. Thus, the supply of fuel to the pot is shortly cut off, as no further fuel passes to the float chamber.

If the operator wishes to re-light the burner and wishes a supply to the burner in preparation for re-lighting, he moves the arm 49 laterally to the position in which it is shown in Fig. 5, which permits the lever 38, 40 to move to release position and permit fuel again to flow into the float chamber. As soon as the burner becomes heated, then the bellows 47 is again in the expanded condition of Figs. 1 and 6, and the control device is again ready to function, as the arm 49 rotates by gravity back into the position in which it is shown in Fig. 6.

Referring to the modified form of Fig. 7, in place of having the support 48 on the top of the bellows, I employ a separate abutment 50, to which the lever 48a is pivoted, it being normally urged downwardly by a spring 51 of insufficient force to resist the expansion of the bellows 47. The arm 49a is then loosely pivoted to the end of the support or lever 48a, and the operation of the device is the same.

It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

I claim:

1. In combination, a burner, a fuel line extending to said burner, a float chamber in said fuel line, a control valve in said float chamber, a float in said float chamber adapted normally to control said valve in response to the level of the liquid fuel in the float chamber, an expansible member responsive to heat changes in the burner, and means for closing said valve in response to the movement of the expansible member, including a valve controlling member extending exteriorly of the float chamber and adapted for manual resetting, and an arm adapted to engage said valve control member, said arm being mounted for rotation about a horizontal axis, vertically aligned with the control member, whereby said arm is normally gravitally aligned with said control member and is in position to engage it when the expansible member contracts.
2. In combination, a burner, a fuel line extending to said burner, a float chamber in said fuel line, a valve associated with said chamber, a float in said chamber adapted to control said valve, and means independent of said float for moving said valve to closed position, including a valve controlling element extending to the exterior of said chamber, an expansible member mounted on the exterior of said chamber, and means for normally maintaining it in expanded position, including a fluid system in communication with the interior of said expansible member, one element of said fluid system being located adjacent the burner and being responsive to the heat of said burner, a member supported on and pivoted to said expansible member and normally gravitally aligned with said outwardly extending valve actuating member and adapted, when the contents of the liquid system becomes cool, to engage said actuating member when the expansible member on the float chamber contracts, and to close the valve.

JAMES L. BREESE.
